UNITED STATES PATENT OFFICE.

JAMES M. CORNELISON, OF ROCHESTER, PENNSYLVANIA.

SAGGAR.

1,264,018.

Specification of Letters Patent. Patented Apr. 23, 1918.

Application filed July 3, 1917. Serial No. 178,443.

To all whom it may concern:

Be it known that I, JAMES M. CORNELISON, a citizen of the United States, and resident of Rochester, in the county of Beaver and State of Pennsylvania, have invented 5 certain new and useful Improvements in Saggars, of which the following is a specification.

This invention relates to new and useful 10 improvements in apparatus for the burning of pottery or like articles, such as emery wheels, and more specifically my invention relates to a new and improved type of sagger, each sagger being formed of a plurality 15 of interengaged sections, and the sections being adapted to be placed in superposed relation, with interlocking means carried thereby, thereby forming a very stable type of stand, which will not fracture or crumble 20 under the intense heat to which devices of this character are subjected.

Another object of the invention is to provide a new and improved type of sagger of 25 this character which is formed with a centrally disposed aperture therein, that is adapted to support a removable filling plug, said plug having a depending pin, that forms a supplemental support therefor, and also a centering means for the emery wheel, 30 or similar article that is disposed within the sagger during the burning operation.

A still further object of the invention is to provide a device of this character which is easily and simply constructed, inexpensive 35 to manufacture, and one which will be very efficient in operation.

With these and numerous other objects in view my invention consists of the novel 40 features of construction, combination and arrangement of parts which will be herein-referred to and more particularly pointed out in the specification and claims.

In the accompanying drawing:

Fig. 1 is a top plan view of my new and 45 improved sagger;

Fig. 2 is a side elevation of the same;

Fig. 3 is a vertical section taken on the line 3—3 of Fig. 1;

Fig. 4 is a top plan view of the slightly 50 modified type of sagger;

Fig. 5 is a section taken on the line 5—5 of Fig. 4; and

Fig. 6 is a further modified form of a sagger.

In describing my invention I shall refer

to the drawings in which similar reference characters designate corresponding parts throughout the several views. My new and improved sagger, which is designated in its entirety by the numeral 1 is formed of a plurality of sections, preferably 1 to 4 in number, each section being formed with, owing to the fact that the sagger is cylindrical, a cylindrical wall portion 2, and a top sector portion 3. The sagger 1 is formed with an open bottom, as it will be understood in which is positioned the pottery, such as an emery wheel or the like, and the same is embedded in sand when so positioned. These saggars are adapted to be placed in superposed relation, forming what is termed a stand, when they are subjected to the burning operation. Each of the sections is provided with a projecting hand hold portion 4, on the outer surface of the cylindrical portion 2, said portions 4 being disposed in alinement, and adapted to form an annular ring, whereby the various sections of the saggars to hold articles may be easily placed in position.

To securely hold the various sections of the sagger in interlocked relation, when the same are in position, I have provided a plurality of rounded projections 5 on one of the edges of each section, which are adapted to register with correspondingly shaped rounded recesses 6 on the adjacent edges of contiguous sections. These projections and recesses extend from the bottom of the sagger sections. This interlocking engagement is clearly shown in Fig. 2 of the drawings, and the same when in operation will securely hold the various sections together to form a very stable article, that will not be likely to slip during the burning operation. In addition to these interlocking means provided for the various sections, the top of the sagger sections is provided on one edge with projecting ribs 7 thereon, and on the other edge a correspondingly shaped annular groove 8, whereby when the sections are placed in position, these ribs and grooves are adapted to register, hence to securely hold said saggars in this position.

The sector portions 3 of the top of the saggars are formed with concaved corners adjacent the point of intersection of the division lines of the structure in the top wall thereof, which are designated by the numeral 9, and which when the sagger sec-

tions are assembled is adapted to form a centrally disposed aperture therethrough. These apertures are formed with stepped shoulders 10 on the inner edge thereof, and 5 adapted to be positioned for each saggars, which is formed with stepped correspondingly shaped shoulders 12 on the marginal edge thereof adapted to engage the shoulders 9 of the apertures.

10 The plugs 11 are primarily supported in the apertures in the tops of the saggars as has been hereinbefore described, and to provide a supplemental supporting means therefor, to prevent said plugs from slipping 15 should the various sections work apart slightly, I provide a supplemental supporting means 14, which comprises a pin having its upper end embedded in the lower surface of the plug, and said pin extending 20 downwardly to a point on the plane of the lower edge of the cylindrical wall portions 2 of the sections of the saggars. Thus it will be obvious that when the saggars are disposed in superposed relation, the bottom of 25 the pin 14 will rest on the top of the plug 11 in the saggars directly beneath the same, to support said first mentioned plug securely in position. This pin forms also a centering means for the structure when the same 30 is used for burning an emery wheel, as the pin is positioned through the aperture in said emery wheel.

In Figs. 4 and 5 of the drawings I have illustrated a slightly modified form of saggars, that is formed in four sections, and 35 which is provided with a slightly modified type of holding means for the plug 11. The plug 11 in this form of the type, and the adjacent portions of the sections are provided with beveled shoulders 15, which are 40 adapted by interlocking engagement to support the plugs when the sections are assembled, as clearly shown in Fig. 5 of the drawings. This plug is provided with the usual 45 type of pin 14 depending therefrom, as used in the other type of the device. This type for supporting the plugs need not necessarily be employed only on the four section saggars, as the same is equally applicable to 50 the saggars formed of three or a greater number of sections, it being only necessary that the shoulders of said sections being beveled so as to co-operatively engage the shoulder on said plug. The various other 55 interlocking features of the saggars are similar no matter how many sections are employed.

In Fig. 6 of the drawings I have shown a comparatively simple type of saggars that 60 is adapted to be employed for making small emery wheels, and which includes a cylindrical body portion 16 provided with an annular hand hold ring 17 projecting laterally from its upper edge, and said ring 65 forms an additional support, so that these

saggars are adapted to be superposed to form a stand. This type of saggars does not employ the type of plugs used in the other saggars, and is only used where the wheels are comparatively small. A plurality of 70 emery wheels are positioned within the cylindrical body portion, the same being embedded in sand, as clearly illustrated in Fig. 6 of the drawings.

In operation these saggars are adapted to 75 be placed in superposed relation, to form a stand, which is subjected to intense heat to burn the article of pottery contained therein. In the formation of this stand, after one saggars is placed in position, a certain 80 amount of sand is poured on the top of the same, and then the other saggars is assembled and placed around the same, with the plug removed, whereupon sufficient sand is poured through the aperture to entirely embed the emery wheel, or other article of pottery contained therein, and then the plug 11 is placed in position in the aperture, the pin 14 extending through said saggars and resting on the top of the plug of the saggars 90 directly beneath the same. This operation is repeated until the stand reaches the desired height.

Although the saggars are formed in sections, the interlocking means on the adjacent 95 edges thereof will securely hold the various sections together and form a very stable article of this character. The saggars are also provided with additional interlocking means to hold them securely in superposed 100 relation, and prevent them sagging or slipping under the intense heat to which they are subjected. The pin 14 in addition to being a centering means for the emery wheel or article of pottery contained in the saggars, 105 also forms a supplemental support for the plug 11 and prevents said plug from slipping through the aperture should the various sections spread slightly. The said shoulder arrangement that primarily supports 110 the plug in position prevents sand from leaking therethrough and forms a very safe and secure means for ordinarily holding said plugs stationary.

It will be understood that the various 115 sections of this saggars are formed of fire clay, and broken portions of old saggars, that are molded in the herein-described shape, and so formed.

From the foregoing description, taken in 120 connection with the accompanying drawings, the advantages of the construction and of the method of operation will be readily apparent to those skilled in the art to which the invention appertains, and while I have 125 described the principle of operation of the invention, together with the device which I now consider to be best embodiment thereof, I desire to have it understood that the device shown is merely illustrative, and that 130

certain changes may be made when desired as are within the scope of the claims appended hereto.

Having fully described my invention what I claim as new, and desire to secure by Letters Patent, is:

1. A saggar of the class described including a sectional body having a centrally disposed aperture in the top thereof, a plug 10 removably filling said aperture and supported therein, and supplemental supporting and centering means depending from said plug.
2. A saggar of the class described including a sectional body having a centrally disposed aperture in the top thereof, a plug 15 removably filling said aperture and supported therein, a plurality of correspondingly

stepped shoulders on the inner surface of said aperture and the plug to support said plug, and supplemental supporting and centering means depending from said plug. 20

3. A saggar of the class described including a sectional body having a centrally disposed aperture in the top thereof, a plug 25 removably filling said aperture, a plurality of correspondingly stepped shoulders on the inner surface of said aperture and the plug to support said plug, and a pin depending from said plug and extending through the body to a point in the plane of the lower 30 edge thereof.

In testimony whereof, I affix my signature hereto.

JAMES M. CORNELISON.
